UNITED STATES PATENT OFFICE

GASTON PERRET, OF PARIS, FRANCE

DEVICE FOR TENSIONING CRIMPED LACE IN THE COURSE OF WEAVING

Application filed February 27, 1930, Serial No. 431,797, and in France March 2, 1929.

The present invention relates to a device for constantly tensioning on the loom lace, tape, webbing, galloon or the like (hereinafter referred to as "lace") of the kind that is crimped or puckered on a portion of its width from one selvage thereof. index operating knob or handle associated with the roller-supporting frame for accurately adjusting the distance between said rollers.

The primary object of the invention is the provision of a device readily adaptable on lace weaving looms for frictionally acting on the crimped or puckered side of the lace being woven in such a way as to accelerate the rate of feed of said crimped side while holding it well taut whereby at each pick the shuttle can always traverse the whole lap of warp threads substantially at right angles thereto and the texture of the lace is thus uniform throughout its width.

20 A further object of the invention is the provision of a lace tensioning device of simple and cheap construction and operation adapted for permitting the frictional accelerating action on the crimped side portion of the lace to be readily adjusted in a most precise way depending on the thickness and/or nature of 25 the lace and the additional length of its crimped or puckered side portion with respect to its plain or non-crimped side portion.

30 Numerous other objects and advantages of the invention will be apparent as it is better understood from the following description which, taken in connection with the accompanying drawings, discloses a preferred embodiment thereof.

Referring to the drawings:

35 Figure 1 is a perspective view of the complete tensioning device according to the invention as secured against the framework of the lace weaving loom, the line passing between the rollers illustrating in a diagrammatic way the path followed by the lace, the rectilinear arrows showing how the lace is held taut by the rollers before passing between them and floats in the crimped or puckered state after having passed between them.

Figure 2 is a fragmentary perspective view somewhat diagrammatic setting forth in a still clearer way the tensioning effect of the device upon the lace.

Figure 3 is a fragmentary plan view of an

Figure 4 is a diagrammatic elevational view of an adjustable clutch gear interposed between the usual actuating mechanism of the loom and the tensioning device according to the invention.

Figure 5 is a diagrammatic fragmentary edge view of the clutch gear shown in Figure 4.

Like references designate like parts throughout the several views.

As illustrated, the tensioning device is adapted to be secured to the framework A of the lace weaving loom, for example by means of screws a passing through a base plate 1. Against the latter is adjustably secured, by means of screws 2, a fish plate 3 formed with horizontal slots 3^a through which said screws 2 may be adjusted whereby the longitudinal position of said fish plate 3 may be regulated with respect to the framework A. Against the fish plate 3 is held in a similar way a smaller fish plate 4 formed with vertical slots 4^a through which protrude screws 5 fixed to the fish plate 3 and adjustable in said slots 4^a whereby the vertical position of the fish plate 4 can be regulated with respect to the framework A.

It will thus be seen that the position of the tensioning device proper, now to be described, can be readily adjusted both lengthwise and heightwise relatively to the stationary framework A.

The fish plate 4 has formed integral therewith or permanently fixed thereto two cheeks 6, 7 substantially at right angles to its plane. The cheek 6 is formed with a cylindrically bored headstock 8 in the bore of which is fixedly housed the lower part of a straight spindle 9 on the upper part of which is slidably but non-revolubly fitted a companion cylindrically bored headstock 10 the bore of which is screw-threaded at its upper end for the engagement of the correspondingly screw-threaded tail 11 of a circular knob or handle 12 preferably knurled or otherwise roughened on its rim to provide a better grip. The

knob 12 is centrally hollowed for accommodating a grub screw 9^b screwed on the reduced and screw-threaded top of the spindle 9. The periphery of this grub screw 9^b is 5 notched or nicked as at 9^a to provide a stationary index. The upper surface of the knob 12 is formed with index grooves 12^a which may be angularly caused to register with the index notch 9^a, index numbers being 10 advantageously provided as shown in Fig. 3.

Other kinds of co-operating indices on the screw 9^b and knob 12 might of course be provided, as will be readily understood.

The upper headstock 10 has formed integral therewith a bracket 13 having two cheeks 14, 15 substantially aligned with the lower cheeks 6, 7. Through the latter are journalled the ends of a horizontal pin 16 and through the cheeks 14, 15 are similarly journalled the ends of a horizontal pin 17.

On each pin 16 and 17 is keyed or otherwise secured a friction roller 18 and a pinion 19, the peripheral surface of said rollers or at least of one of them being advantageously 20 knurled or otherwise roughened to ensure a better grip on the lace and circumferentially notched laterally as at 18^a for a purpose to be specified hereafter. The diameters of the rollers 18, 18 and pinions 19, 19 are so reckoned that, when the teeth of the one pinion 20 fully mesh with the teeth of the other pinion, the peripheral surfaces of both rollers are in close contact.

With the lower pinion 19 constantly 25 meshes a further pinion 20 keyed or otherwise fixed upon a pin 21 having its ends journalled in the cheeks 6, 7. The pinion 20 constantly meshes in turn with a further pinion 22 keyed on a pin on which is also keyed a sprocket wheel 23 connected by a chain 24 with another sprocket wheel 25 forming part of the clutch gear operatively connected to the actuating mechanism of the loom, as will be more fully described hereafter. By this arrangement, the friction rollers 18, 18 are automatically rotated in opposite directions as shown by the curvilinear arrows in Fig. 1 by the very operation of the loom.

The adjustable clutch gear illustrated in Figs. 4 and 5 is interposed between the usual actuating mechanism (not shewn) of the loom and the chain 24 for adjusting the rotational speed of the rollers 18, 18 in accordance with the nature of the crimped or puckered lace that is being woven.

The sprocket wheel 25 of the adjustable clutch gear is removably mounted on a shaft 26 supported by the loom framework and carrying a pinion 27 meshing with a smaller pinion 28 keyed on a stub shaft 29 fitted with a pinion 30 meshing with a smaller pinion 31 keyed in turn to a stub shaft 32 journalled in a forked bracket 33 and carrying a ratchet wheel 34 with which co-operate a retaining pawl 35 and a feeding pawl 36, the latter

being provided on the upper end of an upstanding rod 37 fulcrumed on a fixed point of the apparatus and pivotally connected at 37^a to a link 38 pivotally connected at 38^a to a crank portion 39. The latter is formed 70 intermediate its ends with an elongated slot 39^a through which protrudes the shank of a bolt fitted with a nut 40 the purpose of which is to adjustably connect it to a companion crank portion 41 jointedly connected at 42 to 75 an eccentric part of a wheel 43 connected by its shaft 44 to the mechanism actuating the lace weaving loom. This mechanism is of normal structure and has therefore not been 80 illustrated.

In view of the foregoing, the operation of the tensioning device as operated by the above-described gear will now be readily understood.

As above stated, the problem to be solved 85 consists in constantly holding well taut the crimped or puckered side portion G^b of the lace G the other side portion G^a (not crimped or only very slightly crimped) of which is usually stiffened by some sort of wire W imbedded in the hemmed selvage of the non-crimped side portion so that the warp threads 90 in the crimped portion G^b which are, of course, longer (say twice longer) than the warp threads in the non-crimped portion G^a 95 should nevertheless be held as tensioned as the latter whereby at each pick the shuttle (not shown because of conventional structure) of the loom should always traverse the whole lap of warp threads substantially at 100 right angles thereto and the texture of the lace is thus uniform throughout its width.

The aforesaid problem is readily solved by the operation of the tensioning device according to the invention since the crimped or 105 puckered side portion G^b of the lace is engaged between the friction rollers 18, 18 whose distance may be adjusted at will by means of the index knob or handle 12 and whose rotational speed may be regulated by the above-described clutch gear, as will be stated hereafter, to cause the rate of feed of the crimped side portion G^b of the lace to always 110 catch up the rate of feed of its plain side portion G^a regardless of the discrepancy in 115 length of their respective warp threads. It will be seen that by the frictional action of the rollers 18, 18 on the crimped or puckered side portion of the lace, the latter is necessarily held well taut before passing between the rollers.

If, as is often the case with lace of this character, a stiffening wire W is imbedded in the hemmed selvage of the non-crimped side portion G^a, the hem thus reinforced will 120 freely pass through the side notches 18^a without interfering with the proper action of the rollers.

By regulating the angular position of the 125 knob 12 so as to vary the mutual positions of

its indices 12^a and the index 9^a on the grub screw 9^b, the distance between the friction rollers will be very accurately adjusted for example to suit the thickness or nature of the lace in the course of weaving.

The adjustment of the speed of rotation of the rollers 18, 18 can be easily performed by regulating the operative length of the composite crank 39—41. To that effect, it is merely necessary to loosen the nut 40 and slide the crank portion 39 outwardly or inwardly of the crank portion 41. By thus adjusting the length of the crank 39—41, it is obvious that the throw of the rod 37 and pawl 36 will be varied whereby the rotational speed of the reducing gear interposed between the ratchet wheel 34 and the sprocket wheel 25 will be correspondingly adjusted in the most precise way.

Adjustment of the rotational speed of the rollers 18, 18 might also be performed by substituting a larger or smaller sprocket wheel 25 for the one used. However it will be appreciated that in the majority of cases the adjustment of the operative length of the composite crank 39—41 will be much easier.

The whole of the gear as illustrated in Figs. 4 and 5 is suitably supported by the framework of the loom, said framework not being shown as forming no part of the invention and being of conventional structure.

Numerous minor constructional details of the device might of course be changed without departing from the spirit of the invention. Thus for instance horizontal slots might be formed in the outer fish plate 4 and vertical slots might be formed in the inner fish plate 3. The shape of the roller-supporting frame might also be changed.

What I claim is:

1. A device for tensioning crimped lace of the type set forth in the course of weaving comprising, in combination, a two-part frame having means for adjustably securing it to the loom framework, a pair of parallel cylindrical friction rollers journalled in the respective parts of the frame and adapted to grip the crimped side portion of the lace between them, an adjustable clutch gear interposed between the usual actuating mechanism of the loom and the rollers, and index operating means associated with said frame for accurately adjusting the distance between the rollers.

2. A device for tensioning crimped lace of the type set forth in the course of weaving comprising, in combination, a frame formed of two vertically aligned bored headstocks connected to each other by a spindle engaging their bores, each headstock having a pair of spaced upstanding cheeks, a pair of parallel cylindrical friction rollers journalled in the respective pairs of cheeks and adapted to grip the crimped side portion of the lace between them, an adjustable clutch gear interposed

between the usual actuating mechanism of the loom and the rollers, index operating means associated with the spindle and upper headstock for accurately adjusting the distance between the rollers, and means for adjustably securing the lower headstock to the loom framework.

3. A device for tensioning crimped lace of the type set forth in the course of weaving comprising, in combination, a frame formed of two vertically aligned bored headstocks connected to each other by a spindle engaging their bores, the upper headstock being internally screw-threaded over a portion of its length, each headstock having a pair of spaced upstanding cheeks, a pair of parallel cylindrical friction rollers journalled in the respective pairs of cheeks and adapted to grip the crimped side portion of the lace between them, an adjustable clutch gear interposed between the usual actuating mechanism of the loom and the rollers, a bored knob bearing indices and engaging the screw-threaded portion of the upper headstock, a screw bearing an index accommodated in the bore of the knob and screwed into the adjacent end of the spindle, and means for adjustably securing the lower headstock to the loom framework.

4. A device for tensioning crimped lace of the type set forth in the course of weaving comprising, in combination, a frame formed of two vertically aligned bored headstocks connected to each other by a spindle fixed to the lower headstock and slidably engaging the bore of the upper headstock, said upper headstock being internally screw-threaded over a portion of its length, each headstock having a pair of spaced upstanding cheeks respectively aligned with the cheeks of the companion headstock, a pair of parallel cylindrical friction rollers cut away on a portion of their width to form a side passage between them, said rollers being journalled in the respective pairs of cheeks and adapted to grip the crimped side portion of the lace between them, an adjustable clutch gear comprising ratchet and sprocket wheels interposed between the usual actuating mechanism of the loom and the rollers, a bored knob bearing indices and engaging the screw-threaded portion of the upper headstock, a grub screw bearing an index accommodated in the bore of the knob and screwed upon the adjacent end of the spindle, and a pair of fish plates having respective slots at right angles to each other, one of said fish plates being fixed to the lower headstock, said plates being adjustably secured to each other and to the loom framework by screws engaging their slots and held therein by nuts.

In testimony whereof I affix my signature.
GASTON PERRET.
